UNITED STATES PATENT OFFICE.

CHARLES A. BILLS, OF ST. JOE STATION, INDIANA.

DERRICK.

SPECIFICATION forming part of Letters Patent No. 691,349, dated January 21, 1902.

Application filed October 10, 1901. Serial No. 78,250. (No model.)

To all whom it may concern:

Be it known that I, CHARLES A. BILLS, a citizen of the United States, residing at St. Joe Station, in the county of Dekalb and State of Indiana, have invented a new and useful Derrick, of which the following is a specification.

My invention is an improved derrick, particularly adapted for hoisting stones and other heavy weights; and it consists in the peculiar construction and combination of devices hereinafter fully set forth and claimed.

In the accompanying drawings, Figure 1 is a side elevation of a derrick constructed in accordance with my invention. Fig. 2 is a detail sectional view taken on a plane indicated by the line *a a* of Fig. 1 and showing the winches for operating the counterpoise-boom and the lowering-tackle. Fig. 3 is a similar view taken on a plane indicated by the line *b b* of Fig. 1. Fig. 4 is a side elevation of the upper portion of the mast, showing the drum therein on which the elevating-rope operates that raises and lowers the boom. Fig. 5 is a similar view, partly in section, of the lower portion of the mast, showing the means for operating the said drum. Fig. 6 is a detail elevation showing one of the brakes.

In the embodiment of my invention I employ a mast 1, which is journaled at its upper and lower ends in a suitable supporting-frame 2. Thereby the mast is adapted to turn axially. At the lower ends of the mast, fast with and adapted to turn therewith, is a platform 3. A pair of cross-bars 4 are secured on opposite sides of the mast at a suitable distance from the lower end thereof, and the said cross-bars are provided at opposite ends with bearings for a hoisting-boom 5 and a counterpoise-boom 6, which are disposed on opposite sides of the mast, as shown in Fig. 1. The said hoisting-boom is provided near its outer end with pulleys 7 8.

The counterpoise-boom carries a weight 9 at its outer end. As here shown, the said weight is a tank adapted to carry a variable quantity of water, according to the weight which is to be hoisted by the derrick. The said counterpoise-boom also carries near its outer end a pair of pulleys 10 11.

50 The mast is provided near its upper end

with bearings, as at 12, for a drum 13. The shaft of the said drum is provided on one side of the said mast with a brake-drum 14 and with a sprocket-wheel 15. (See Fig. 4.) A hoisting-rope 16 is attached to the boom 5 near the outer 55 end of the latter, passes over and is partially coiled upon the drum 13, passes over the pulley 11, carried by the counterpoise-boom, and is attached to a winch 17, which is carried by the counterpoise-boom, and is disposed on 60 the lower side thereof near its inner end. The winch 17 is provided at one end of its shaft with a spur-gear 18 and at the opposite end thereof with a brake-drum 19. A brake-band 20 engages one side of the said brake- 65 drum. One end of the said brake-band is secured to the counterpoise-boom and the other end thereof is connected to the crank 21 of a rock-shaft 22. The said rock-shaft has a crank handle or lever 23, by which it may be 70 actuated to apply the brake-band frictionally to the drum or release it therefrom. The said winch 17 is adapted to pay out or reel in the hoisting-rope 16 in order to dispose the counterpoise-boom at any desired angle with 75 relation to the hoisting-boom, according to the extent to which the latter must be raised when elevating a weight.

The lowering-rope 24 is attached to a block 25, which has a pulley 26, and is provided 80 with grappling-hooks or other devices 27 for engaging or supporting the weight, as is here indicated at X, Fig. 1. The said lowering-rope passes over the pulley 8, under the pulley 26, and over the pulley 7. The said lowering-rope and said pulleys 7, 8, and 26 constitute a lowering-tackle, and the same may be varied as may be required by the weights to be handled thereby. Said lowering-rope 24, as here shown, passes through a guide- 85 slot 28, with which the mast is provided, passes over the direction sheave or pulley 10, with which the counterpoise-boom is provided, and is attached to and adapted to be reeled upon or unreeled from a winch 29, which is 90 similar to the winch 17, has a gear-wheel 30 disposed at some distance from the gear 18, and is provided with a brake 31, which is 95 similar to that with which the winch 17 is provided. A shiftable shaft 32 is journaled at 100

one end in a fixed bearing 33, in which it is loose. The said shiftable shaft is journaled near its opposite extremity in a shifting-bar 34. The said shifting-bar is fulcrumed on 5 the counterpoise-boom, as at 35. An operating-lever 36 is also fulcrumed on the said counterpoise-boom and is connected to the said shifting-bar by a rod 37. Hence by operating the shifting-lever 36 the shifting-bar 10 34 and the shiftable shaft 32 may be moved to cause a pinion 38, with which said shaft is provided, to be engaged with either the gear 18 or the gear 30 at will. The said shiftable shaft has a crank-lever 32a, by which it may 15 be turned.

A shaft 39, which has a gear-wheel 40 and a sprocket-wheel 41 fast thereto, is journaled in a bearing at a suitable distance from the lower end of the mast. The said shaft has 20 a crank 42 at one end. The gear 40 is engaged by a pinion 43, which is carried by a shaft 44, that has a crank 45, which is disposed on the opposite side of the mast from the crank 42. Said shaft 44 also has its bearing 25 in the mast. An endless sprocket-chain 46 connects the sprocket-wheels 15 and 41, and hence when the latter is rotated either by the crank 42 or the crank 45 power is communicated through the chain 46 and the sprocket-wheel 15 to the drum 13, and the rope 16 is 30 operated by the said drum to simultaneously move the boom 5 and the counterpoise-boom in the same direction. Since the said booms are on opposite sides of the mast, it follows 35 that one will be elevated while the other is being lowered. By paying out or taking in the hoisting-rope 16 the boom 5 and counterpoise-boom 6 may be disposed at any desired angle with reference to each other, according 40 to the extent to which the outer end of the boom 5 must be raised to elevate a weight to the required height. Since the weight is carried by the boom 5 and counterpoised by the weighted counterpoise-boom, it is evident that 45 comparatively slight power is required to operate the hoisting-rope 16 after the boom 5 and the counterpoise-boom have been adjusted and to raise the weight. When the weight has been raised to the required height and 50 the mast swung so as to dispose the weight over the point to which it has been lowered, the shiftable shaft 32 is shifted to engage its pinion 38 with the gear 30 of the lowering-winches 29, which operates the lowering-tackle, 55 by which the weight is lowered, the boom 5 and the counterpoise-boom being securely held against movement during the lowering of the weight by a brake-band 47, which is operated by a bar 48. A spring 49, which 60 bears on the said bar 48, normally keeps the brake-band 47 in engagement with the brake-drum 14. A releasing pedal-lever 50, which is fulcrumed near the lower end of the mast and is connected to the bar 48 by a rod or 65 cord 51, is provided for releasing the brake-

band 47 from the drum 14 when the drum 13 is operated, as hereinbefore stated, to raise the weight.

Having thus described my invention, I claim—

1. In a derrick, the combination of a hoisting-boom, a counterpoise-boom, a drum supported at an elevated fixed point, a rope connecting said booms and partly coiled on said drum, and means to rotate the latter, and thereby simultaneously operate said booms, substantially as described. 70

2. In a derrick, the combination of a hoisting-boom, a counterpoise-boom, a rope connecting them, means to vary the length of said rope between said booms, to adjust the latter to any desired angle, and means to operate said booms simultaneously, substantially as described. 80

3. In a derrick, the combination of a mast, a hoisting-boom and counterpoise-boom carried by and on opposite sides of said mast, a hoisting-rope connecting said booms and engaging an operating element with which the mast is provided, means to vary the length 90 of said hoisting-rope, between the said booms, to adjust the latter, a lowering-tackle carried by the hoisting-boom and means carried by the counterpoise-boom to operate said lowering-tackle, substantially as described. 95

4. In a derrick, the combination of a mast, a hoisting-boom and counterpoise-boom carried thereby and on opposite sides of said mast, a hoisting-rope connecting the said booms, a winch carried by the counterpoise-boom to pay out and take in said hoisting-rope and thereby adjust said booms, a lowering-tackle carried by the hoisting-boom, a lowering-winches carried by the counterpoise-boom to which said lowering-tackle is connected, gears on the said winches, respectively, and a shiftable shaft having a power element and a pinion, the latter being adapted to be shifted by said shaft into engagement with either of said winch-gears at will, substantially as described. 100

5. In a derrick, the combination of a mast having a hoisting-drum, means to operate the same, and a brake therefor, a hoisting-boom and counterpoise-boom carried by said mast 115 on opposite sides thereof, a hoisting-rope connecting said booms and engaged by said hoisting-drum, a winch carried by said counterpoise-boom to adjust said hoisting-rope, a lowering-tackle carried by said hoisting-boom, 120 and a winch carried by said counterpoise-boom to operate said lowering-tackle, substantially as described.

6. In a derrick, the combination of a mast, an elevated hoisting-drum, carried by the 125 mast, a power element, connected to said hoisting-drum, means to lock the latter against rotation, a hoisting-boom, a counterpoise-boom, said booms being carried by the mast, and disposed on opposite sides thereof, a hoisting- 130

rope, connecting said booms and operated by said hoisting-drum, a lowering-tackle, carried by said hoisting-boom, winches carried by said counterpoise-boom, for said hoisting-rope and lowering-tackle, respectively, means to lock said winches against rotation, and a shiftable power element, to operate either of said winches at will, substantially as described.

In testimony that I claim the foregoing as my own I have hereto affixed my signature in the presence of two witnesses.

CHARLES A. BILLS.
